UNITED STATES PATENT OFFICE.

WILLIAM C. ROE, OF PITTSBURGH, PENNSYLVANIA.

AUTOMATIC STOPPING MECHANISM FOR PHONOGRAHS.

Application filed July 17, 1919. Serial No. 311,446.

To all whom it may concern:

Be it known that I, WILLIAM C. ROE, a resident of Pittsburgh, in the county of Allegheny and State of Pennsylvania, have 5 invented a new and useful Improvement in Automatic Stopping Mechanism for Phonographs, of which the following is a specification.

The invention relates to attachments for 10 phonographs or talking machines for the purpose of automatically stopping the rotation of the record carrying table when the needle has reached the end of the record.

The object of the invention is to provide 15 a mechanism of this kind which is entirely automatic and stops the rotation of the table when the tone arm stops moving over the record, entirely irrespective of the length of the record and without the necessity of any special or previous adjustment 20 of the mechanism. A further purpose of the invention is to provide an automatic mechanism for the purpose stated which is of simple and durable construction and reliable in 25 operation.

In the accompanying drawings Fig. 1 is 30 a plan view of a portion of the table of the talking machine having the improvement applied thereto; Fig. 2 is a vertical section 35 on the line 2—2, Fig. 1; Fig. 3 shows the main parts of the mechanism in plan view and on an enlarged scale; Fig. 4 is a detail horizontal section on the line 4—4, Fig. 5, Fig. 5 is a detail vertical sectional view on 40 the line 5—5, Fig. 3; and Fig. 6 is a plan view showing a modification.

In the drawings 1 indicates the box or cabinet within which the phonograph actuating mechanism of the usual construction 45 is mounted; 2 indicates the record mounted on the usual rotary table 3 which is carried by the vertical spindle 4, driven in the usual way from the actuating mechanism; and 5 is the tone arm, shown as of the usual construction, pivotally supported at one side of the table 3 in the usual manner, and carrying the usual sound reproducing box and needle which travels over the record.

The spindle 4, directly underneath the 50 table 3 is provided with, or has applied thereto, a spiral or worm 7 which meshes with a worm wheel 8 on a horizontal shaft 9 mounted in bearings 10 which are shown as formed in up-turned portions of the supporting plate 11 which is secured to the top

of the box 1, underneath the rotary table 3. Pivottally mounted on the plate 11, at 12, is a shifting member comprising an arm 13 and a lever arm 14, the latter extending out beyond the table and being provided with an actuating handle 15. The outer end of the shaft 9 is provided with a worm 16 which meshes with a worm wheel 17 rotatably mounted on the arm 13. As shown (see Fig. 5) the worm wheel 17 is provided with a sleeve 18 which surrounds a headed stud 19 screwed or otherwise secured in the arm 13. Mounted around the sleeve 18, between the worm wheel 17 and the arm 13 is a toothed wheel 20, having inclined or saw teeth as shown in Fig. 4, and arranged to be engaged by a similarly toothed segment 21 on an arm 22 which is secured to the tone arm 5 and moves therewith, said arm 22 preferably being angularly adjustable relative 75 to the tone arm, as by means of the clamping band 6, and also adjustable in length by the screw and slot connection 23, so as to secure proper relation between the segment 21 and the wheel 20. The wheels 17 and 20 80 are so connected that they can rotate relative to each other in one direction but not in the opposite, such, for instance, as providing the gear 20 with a recess 24 containing a cylinder or ball 25 biased by means of spring 26 and arranged to engage the sleeve 18 of worm wheel 17, this forming a well known type of ratchet clutch which permits relative rotation between the gears in one direction but not in the opposite direction, 85 as will be readily understood.

The supporting plate 11 is provided with a radial extension 11^a projecting out into proximity to the periphery of the rotating table 3, and has pivotally mounted thereon, 90 at 28, a lever 29 which at its free end carries a brake member 30 arranged to cooperate with the inner surface of the rim of the table 3, to stop said table in a well understood manner. A tension spring 31 connected at one end to a stud 32 on the supporting plate arm 11^a and at its opposite end connected to a stud 33 on the lever 20, normally biases the brake toward the rim of the table and is of sufficient strength, when allowed to act, to exert sufficient pressure of the brake member 30 against the rim of the table to stop the rotation of the latter. The lever arm 14 is provided with a triangular shaped opening 110

34 through which the stud 33 projects, said opening having two oppositely inclined straight faces 35, 35^a connecting with lateral extensions 36, 36^a at the two ends of the opening 34, and which extensions are circumferential with reference to the axis around which the lever 14 oscillates.

The operation of this mechanism is as follows: Fig. 3 shows the parts in position 10 with the rotating table held against rotation by brake member 30. In this position the worm gear 17 is out of mesh with the worm 16. A new record having been placed upon the table, and the tone arm 15 positioned at one side as usual, the machine is started by moving the lever handle 15 in the direction of the arrow 37, which brings the worm wheel 17 into mesh with the worm 16, and at the same time the inclined face 35 of the opening 34 in the lever 14 rides over the pin 33 and causes the lever 29 to be oscillated around its pivot, thus disengaging the brake member 30 from the rim of the table 3, and permitting the 25 actuating mechanism to start the rotation of the table. The lever 14 is moved until the pin 33 rests in the lateral extension 36 of opening 34, thus holding the lever 29 in table-unlocking position. The needle is 30 then started on the record in the usual way. As the table rotates, through worm 7, worm wheel 8 shaft 9 and worm 16, the worm wheel 17 is also rotated. The tone arm moves over the record in the usual way, and 35 finally toothed segment 21 thereof engages with toothed wheel 20, thus also rotating this wheel, and in the same direction as the wheel 17 is rotated, at the same, or a greater speed, preferably at a greater speed 40 in order to hold the lever 14 and stud 33 in inter-locking engagement. The ratchet clutch 25, 26 is so arranged as to permit these two gears to be rotated in the same direction but at different speeds. This condition continues until the needle reaches 45 the end of the record, whereupon, as is well known, the swinging movement of the tone arm ceases, so that the arm 22 and segment 21 become relatively stationary. This locks 50 the wheel 20 against rotation, and since the ratchet clutch 25, 26 permits relative rotation of the wheels 20 and 17 in one direction only, the locking of the wheel 20 against rotation also locks the wheel 17 55 against rotation. The shaft 9 and worm 16, however, continue to rotate and the thrust of the worm 16 against gear wheel 17 forces the latter away from the worm 16, thus oscillating the arm 13 around its pivot 60 12, which carries with it the lever arm 14. This movement, although slight, is sufficient to oscillate the lever arm 14 sufficiently to allow the stud 33 to pass out of the circumferential extension 36 of opening 34, and 65 on to the inclined face 35,—whereupon the

tension spring 31 causes said stud to press against the inclined face 35 with sufficient force to move the lever 14 with a quick snappy movement still farther in the same direction, until the stud 33 comes to rest 70 in the angle formed by the two inclined faces 35, 35^a,—thus carrying the gear wheel 17 entirely free of worm 16, and allowing the brake member 30 to contact with the rim of the table 4 and stop its rotation. 75 This movement also carries the gear 20 out of the arc of movement of the segment 21, so that when in this position the tone arm can swing freely back and forth.

The mechanism is now in the position 80 that it was in the beginning, and for playing a new record the foregoing operations are repeated.

The inclined face 35 and lateral extension 36 of the opening 34, on the right-hand side, only are brought into action when the mechanism is intended to automatically stop the machine. The opening 34 however is made symmetrical on both sides of its axis, so that the record table can be started and stopped by hand when it is desired to operate the machine in the ordinary way. In that case the inclined face 35^a and lateral extension 36^a, on the left-hand side of the opening, are brought into play. For instance, the record table will be started by moving the handle toward the right, thus causing the pin 33 to ride up the inclined face 35^a until it has entered into the lateral extension 36^a, which locks the brake carrying lever in inactive position. When it is desired to stop the machine the lever is given a movement in the opposite direction sufficient to release the stud 33 from the lateral extension 36^a, whereupon the spring 31 moves the parts back to normal position, with the stud 33 positioned in the angle between the two inclined faces 35, 35^a and with the brake in contact with the rim of the rotary table.

Fig. 6 shows a modification in which the gear wheel carrying-arm 13^a is independent of the lever arm 14^a, both of said arms being independently pivoted on the screw 12. The worm 16^a in this case is made somewhat 115 longer than in Fig. 1, and mounted upon the arm 13^a, at 40, is an angle-shaped lever 41 provided with a nose 42 which engages the worm 16^a. A tension spring 44 is connected to a fixed stud 45 and to the 120 lever 41 so that its axis lies in the axis of the pivot 40, holds the lever 41 normally in position for its nose 42 to engage the worm 16^a, and also holds the arm 13^a toward the left to insure such engagement. As the 125 worm 16^a rotates the nose 42 is carried inwardly, that is toward the center of the machine, until finally it is moved entirely out of engagement with the worm. This 130 swings the lever 41 on its pivot to such posi-

tion that its arm is directly in line with an abutment 46 formed on the lever 14^a. Consequently when the gear 17, carried by the arm 13^a, is forced away from the worm 16^a as herebefore described, the arm of lever 41 thrusts against the abutment 46, thereby oscillating the lever 14^a about its pivot 12, to produce the necessary movement of the lever arm 14^a to cause the disengagement 5 of lateral extension 36 of slot 34 from stud 33, and permitting the spring 31 to snap the lever 13^a to central or normal position. The pivoted lever 41 is for the purpose of mechanically connecting the independent 15 arms 13^a and 14^a so as to cause movement of the latter with the former when the gear 17 is forced out of mesh with the worm 16. For the purpose of causing the arm 13^a to move with the lever 14^a when it is desired 20 to start the machine, the periphery of the hub portion of lever arm 13^a is provided with a lug 47, and the hub portion of the lever arm 14^a is provided with a circumferential slot 48, such lug and slot being so 25 arranged that when in inactive position the lug 47 is in engagement with one end of slot 48, so that when the lever 14^a is moved to start the machine, the arm 13^a is swung in the same direction, thus carrying the gear 30 17 into engagement with the worm 16.

The mechanism described is of simple construction, can be readily applied to any standard phonograph or talking machine, is entirely concealed by the table, is sensitive in operation, yet reliable, and serves to automatically stop the record carrying table whenever the needle reaches the end of the record, entirely irrespective of the length of the record, the stoppage being effected by 40 the tone arm ceasing to move over the record.

I claim:

1. In a phonograph machine, the combination of a brake for stopping the phonograph, and trigger for operating said brake to stop the phonograph, said trigger having two cocked positions, manual means to trip the said trigger from one position, and an automatic mechanism operating without manual interposition to trip the said trigger from the other position.

2. In a phonograph machine the combination of a brake for stopping the phonograph, and trigger for operating said brake to stop the phonograph, said trigger having two cocked positions, from one of which positions the trigger may be thrown manually, and an automatically operated mechanism to throw it in the reverse way when the reproducer reaches a given position.

3. In a phonograph machine, the combination of a brake for stopping the phonograph, and trigger for operating said brake to stop the phonograph, said trigger having 65 two cocked positions, from one of said po-

sitions the trigger may be tripped manually, an automatic mechanism to trip the said trigger from the other position without manual interposition, said trigger having means whereby it may be thrown one way by hand to stop the phonograph, said mechanism being adapted to throw it in the reverse way when the reproducer arm is stopped.

4. In a phonograph machine, the combination of a brake for stopping the phonograph, and trigger for operating said brake to stop the phonograph, said trigger having means whereby it may be cocked to permit the reproducer to reproduce the record and whereby it may be tripped by the reproducer when the advance of the reproducer in the record is checked, said means embracing an arm mounted to rotate directly with, and with the same angular movement of the reproducer arm, and a gear mounted on a pin fastened to rotate on the trigger, there being only one gear interposed between the arm and the said trigger.

5. In a phonograph machine, the combination of a brake for stopping the phonograph, and a trigger for operating said brake to stop the phonograph, said trigger having means whereby it may be cocked to permit the reproducer to reproduce the record, and whereby it may be tripped by the reproducer when the advance of the reproducer on the record is checked, said means embracing only three sets of gear teeth, and a spring for moving the trigger in either of two directions to apply the brake.

6. In a phonograph, a motor shaft for operating the phonograph, stopping means therefor, a trigger for operating the said stopping means, starting means adapted to cock the trigger whereby the phonograph may be started, a reproducer arm for the said phonograph, a gear sector carried by the said arm, a pair of rotatable gear pinions carried on the said trigger, motor shaft-operated means for causing one of the pinions to rotate in one direction, said gear sector being adapted to cause the other pinion to rotate more rapidly in the same direction, and said trigger being adapted to be moved to stop the phonograph when the said gear sector is stationary and the said first pinion is rotating.

7. In a phonograph machine, a motor shaft for operating the phonograph, stopping means for disabling the said motor shaft, a trigger for holding the said stopping means inoperative during the operation of the phonograph, a set of gears for disabling the said trigger when the phonograph has operated to completely play a record, said set of gears comprising a motor driven gear, a phonograph reproducer arm operated gear, and an intermediate clutch mechanism to clutch the said gears and being adapted to

be entirely thrown out of mesh or to be thrown into mesh with the intermediate gear mechanism connecting the other two gears.

8. In a phonograph machine, a motor shaft for operating the phonograph, stopping means for disabling the said motor shaft, a trigger for holding the said stopping means inoperative during the operation of the phonograph, a set of gears for disabling the said trigger when the phonograph has operated to completely play a record, said set of gears comprising a motor-driven gear, a phonograph reproducer arm operated gear, and intermediate gear mechanism, said gears being adapted to be entirely thrown out of mesh or to be thrown into mesh with the intermediate gear mechanism connecting the other two gears, a pair of pinions associated with the said intermediate gear mechanism, each being adapted to rotate in one direction, and a clutch operative only when the rotative speed of a certain one of the said pinions is in excess of the rotative speed of the other pinion.

9. In a phonograph machine, a motor shaft for operating the phonograph, stopping means for disabling the said motor shaft, a trigger for holding the said stopping means inoperative during the operation of the phonograph, a set of gears for disabling the said trigger when the phonograph has operated to completely play a record, said set of gears comprising a motor-driven gear, a phonograph reproducer arm operated gear, intermediate gear mechanism, said gears being adapted to be entirely thrown out of mesh or to be thrown into mesh with the intermediate gear mechanism, means associated with the said intermediate mechanism adapted to permit a diversity of speeds between motor shaft-driven and reproducer arm-driven elements thereof so long as the arm-driven element is moved in

excess of the speed of the motor shaft-driven element, spring means to hold the gears and mechanism in operative contact, and means responsive to a lower speed of the element driven by the said reproducer arm to disable the said spring means and the said trigger.

10. In a phonograph machine, a motor shaft for operating the phonograph, stopping means for disabling the said motor shaft, a trigger for holding the said stopping means inoperative during the operation of the phonograph, a set of gears for disabling the said trigger when the phonograph has operated to completely play a record, said set of gears comprising a motor driven gear, a phonograph reproducer arm operated gear, and an intermediate gear, said gears being adapted to be entirely thrown out of mesh, one with the other or to be thrown into mesh with the intermediate gear connecting the other two gears, means associated with the said intermediate gear adapted to permit it to rotate in one direction and to prevent it from rotating in the reverse direction, the other two gears tending to rotate the intermediate gear in the same direction, but the said reproducer arm gear being adapted to rotate the intermediate gear at a higher speed than the said other gear would otherwise rotate it, said other gear being adapted to force the intermediate gear out of mesh with the teeth of the said other gear when the said reproducer arm gear becomes stationary when the phonograph record has been completely reproduced.

In testimony whereof, I have hereunto set my hand.

WILLIAM C. ROE.
